UNITED STATES PATENT OFFICE.

PETER M. AZOLINE AND ALBERT J. AZOLINE, OF TORRINGTON, CONNECTICUT.

INCUBATOR ATTACHMENT.

1,265,717.

Specification of Letters Patent.

Patented May 7, 1918.

Application filed October 4, 1917. Serial No. 194,751.

To all whom it may concern:

Be it known that we, PETER M. AZOLINE and ALBERT J. AZOLINE, citizens of the United States, residing at Torrington, in the county of Litchfield and State of Connecticut, have invented certain new and useful Improvements in Incubator Attachments, of which the following is a specification.

This invention relates to incubators and 10 more particularly to thermometer supporting attachments therefor.

The object of the invention is to provide a simply constructed and efficient support or carrier for a thermometer which may be operated from outside an incubator to shift the 15 position of the thermometer to bring it into easy reading distance or to dispose it at the center of the incubator chamber without necessitating the opening of the incubator door 20 thereby preventing all danger of spoiling the hatch by the admission of air currents.

Another object is to so mount a carrier of this character that all possibility of tilting thereof is avoided.

25 Another object is to so construct a carrier of this character that the simple turning of the knob will cause the thermometer carried thereby to appear or disappear at the will of the operator.

30 With the foregoing and other objects in view, which will appear as the description proceeds, the invention resides in the combination and arrangement of parts and in the details of construction hereinafter described and claimed, it being understood 35 that changes in the precise embodiment of the invention herein disclosed may be made within the scope of what is claimed without departing from the spirit of the invention.

40 In the accompanying drawings:—

Figure 1 represents a side elevation with parts broken out of an incubator showing this improved attachment applied and with the thermometer in position for reading,

45 Fig. 2 is a horizontal section taken on the line 2—2 of Fig. 1, and

Fig. 3 is a vertical section taken on the line 3—3 of Fig. 1.

In the embodiment illustrated, an incubator 1 of ordinary construction is shown 50 having the usual incubating chamber 2 and which is here shown provided with double doors 3, although obviously a single door may be employed if found desirable to do so. This incubator proper constitutes no

part of this invention and hence will not be described in detail.

The thermometer carrier constituting the invention is mounted in the incubating chamber 2 and is movable transversely 60 thereof on laterally spaced track rails 4 which extend from front to rear of the incubator as is shown clearly in Figs. 2 and 3 and are arranged at an oblique angle, preferably about 15° from the front toward the 65 rear (see Fig. 2) to facilitate the movement of the carrier thereon without binding. A spacing block 4' carried by the inner face of top 7 of the incubator, spaces the rails a suitable distance from said top (see Fig. 3). 70 The carrier proper 5 is mounted to slide on these rails 4 and as shown is composed of a single piece of wire bent to form arms 6 and 7 which have eyes 8 through which the track rails 4 pass and operate as guides for the 75 carrier. A U-shaped member 9 connects the inner ends of the arms 6 and 7 extending at right angles therefrom as is shown clearly in Figs. 1 and 3 and supported on the cross bar 10 thereof is a thermometer 11 which 80 may be of any suitable or desired construction and is here shown mounted on a base plate having a rolled top 12 which is pivotally engaged with the cross bar 10 of the U-shaped member 9 of the carrier. It will 85 thus be seen that when this carrier is moved on the track rails that the thermometer depending therefrom will be brought toward or away from the front of the incubator so that it may be normally disposed at the center 90 of the incubating chamber above the eggs, in which position it will be exposed to the greatest heat contained in the incubating chamber. When moved toward the front the thermometer 11 will be brought adjacent 95 to an opening 13 formed in the front wall thereof and which is covered by a transparent pane 14 of glass, mica, or other suitable material and through which the thermometer may be readily read. 100

The arm 7 of the carrier has a depending loop 15 through which extends the end 16 of a carrier actuating lever 17. This lever 17 is shown in the form of a bell-crank fulcrumed on a screw 18 which depends from 105 the top of the incubating chamber and the other end of said lever which is bent to form a right-angularly disposed arm 17' passes through a loop 19 depending from a rod 20 which extends transversely of the incubating 110

chamber and is mounted to turn in a bracket 21 depending from the top of the incubating chamber as is shown clearly in Fig. 3. This rod 20 has one end thereof extended through the front wall of the incubator and provided with a finger hold 22 to facilitate the turning thereof. It will thus be seen that when this rod 20 is turned in one direction or the other it will operate to rock lever 17 and 10 shift carrier 5 toward or away from the front of the incubator according to the direction in which the rod is turned. In the drawings the parts are shown in the position which they assume when the carrier is at the front of chamber 2, the lever 17 being rocked on its fulcrum to cause it to move the carrier toward the front of the incubating chamber so as to position the thermometer adjacent the transparent cover 14 of the opening 13. This rod 20 when turned in the opposite direction causes the lever 17 to be rocked in the opposite direction and thereby to slide the carrier 5 inwardly to position the thermometer supported thereby at the 15 hottest part of the incubating chamber.

It will thus be seen that by simply turning the loop or head 22 of rod 20 the thermometer 11 will be advanced or retracted at the will of the operator and without necessitating the exposure of the eggs to draft, such as is occasioned on the opening of the incubator door.

From the foregoing description, taken in connection with the accompanying drawings, the advantages of the construction and of the method of operation will be readily apparent to those skilled in the art to which the invention appertains, and while we have described the principle of operation of the invention together with the device which we now consider to be the best embodiment thereof, we desire to have it understood that the device shown is merely illustrative and that such changes may be made as are within the scope of the claimed invention.

We claim:—

1. The combination with an incubator having an opening in one wall provided with a transparent cover; of a track in the egg chamber of said incubator above the plane occupied by the eggs, a thermometer carrier mounted to travel on said track, said track being arranged at an oblique angle to the wall having the opening therein and from which the track extends to facilitate the movement of the carrier thereon without binding.

2. The combination with an incubator having an opening in one wall provided with a transparent covering; of a pair of laterally

spaced track rails extending from the wall having arms slidably engaged with said rails, site side of the incubator; a U-shaped carrier having arms slidably engaged with said rails, a thermometer carried by said carrier, a lever engaged with said carrier, and means located outside said incubator and engaged with said lever for actuating it to move said carrier toward and away from said opening.

3. The combination with an incubator having an opening in one wall provided with a transparent covering, of a pair of laterally spaced track rails extending from the wall having the opening therein, toward the opposite side of the incubator, a U-shaped carrier having arms slidably engaged with said rails, a thermometer carried by the cross bar of said carrier, a lever engaged with one of said arms, a rotatable rod arranged transversely in said incubator, and engaged with 80 said lever, and means outside said incubator for turning said rod whereby the lever is rocked and the carrier moved toward or away from said opening.

4. An incubator having a transparency in one side wall thereof, a track arranged in said incubator adjacent said transparency, a carrier mounted to slide on said track and having a thermometer depending therefrom; a rod extending transversely of said incubator; means operable from outside said incubator for rotating said rod, a lever disposed between said track and rod and fulcrumed intermediately of its ends, one end of said lever being engaged with said rod and the other end with said carrier whereby the movement of the rod operates to reciprocate the carrier to move it toward or away from the transparency in the wall of the incubator.

5. The combination with an incubator chamber; of a pair of laterally spaced track rails extending thereacross, a carrier mounted to slide on said rails; a thermometer depending from and secured to said carrier and held securely against tilting, a lever fulcrumed intermediately of its ends, and engaged at one end with said carrier; a rod rotatable in said incubator and engaged with the other end of said lever whereby the thermometer may be moved transversely of the incubator chamber from the exterior thereof.

In testimony whereof we affix our signatures in presence of two witnesses:

PETER M. AZOLINE.
ALBERT J. AZOLINE.
